CLAIM

An ornamental design for a wireless transceiver, as shown and described.

DESCRIPTION

FIG. 1 is a front right prospective view of an embodiment of a wireless transceiver according to the present invention;

FIG. 2 is a left side elevational view. A right side elevational view is not shown since it is identical to FIG. 2;

FIG. 3 is a rear elevational view;

FIG. 4 is a bottom view; and,

FIG. 5 is a top view.

FIG. 1

FIG. 2

FIG. 3

FIG. 4

FIG. 5
